UNITED STATES PATENT OFFICE

2,019,366

DIRECTION SIGNAL

John A. Spina, Madera, Calif.

Application June 4, 1934, Serial No. 729,023

1 Claim. (Cl. 177—329)

This invention relates to direction signals for motor vehicles and has for the primary object the provision of a device of the above stated character which will permit a driver of a motor vehicle to conveniently indicate right or left turns by the illumination of different colored signals, eliminating the necessity of hand signals and provides a device which will be clearly noticeable from a considerable distance and especially at night time to materially reduce traffic accidents.

With these and other objects in view this invention consists in certain novel features of construction, combination and arrangement of parts to be hereinafter more fully described and claimed.

For a complete understanding of my invention, reference is to be had to the following description and accompanying drawing, in which

Figure 1 is a fragmentary front elevation illustrating the application of a direction signal thereto and which is constructed in accordance with my invention.

Figure 2 is a transverse sectional view illustrating the same.

Figure 3 is a vertical sectional view illustrating the signal.

Figure 4 is a detail sectional view showing the means of removably securing opposite walls of the signal casing in assembled position.

Figure 5 is a diagrammatical view showing a wiring diagram and switch mechanism to effect operation of the signals.

Fig. 6 is a detail sectional view illustrating a modified form of illumination means for the signal.

Referring in detail to the drawing, the numeral 1 indicates a casing having secured to its bottom wall an arcuately curved bracket 2 apertured to receive fasteners 3 for removably securing the casing to a fender or mudguard of a motor vehicle. While this invention is illustrated as mounted to the fender or mudguard of the motor vehicle it is to be understood that it may be secured to any other place upon the vehicle which will position it in view to approaching traffic of the vehicle.

The casing 1 is of substantially rectangular shape positioned horizontally upon the vehicle and front and rear walls 4 are removably secured to the casing by means of stud bolts 5 extending through said front and rear walls and threaded to angle iron brackets 6 welded or otherwise secured to the casing. The front and rear walls of the casing are cut away or slotted in the shape of arrows 7 forming signals. The ar-

rows of each wall point in opposite directions and the uppermost arrows of said walls point in the same direction to indicate a turn in one direction and the lowermost arrows point in the same direction to indicate a turn in an opposite direction. Mounted in the casing in rear of the arrows are transparent panels 8 which are supported by brackets 9 formed on the casing and also by brackets 10 receiving a partition 11. The partition 11 divides the casing into upper and lower compartments. Each compartment has an arrow pointing in an opposite direction which arrows are arranged at opposite sides of the casing.

Mounted within the casing is a light supporting frame 12, the ends of which are offset to form the brackets 10 and said frame is of skeleton formation composed of end members and upper and lower members with opposite sides thereof open. The end members of the frame are offset to form rests 13 contacting with the casing. The lower member of the frame engages with inclined blocks 14 located in the bottom of the casing, the purpose of which is to properly position the electrical illuminating means 15 carried by the frame in alignment with the arrows 7. The illuminating means 15 may be in the form of neon tubes, as shown in Figure 3, or a series of small electric lamps 16, as shown in Figure 6. The neon tubes 15 when employed are supported in openings formed in the end members of the frame with a neon tube in each compartment. It is preferable that these neon tubes be of different colors so that the arrows pointing in opposite directions will be distinguishable by the different colored light rays. The neon tubes at one end are electrically grounded to the casing by contacts 17, while the opposite ends engage with contacts 18 insulated from the casing and are connected to conductors 20 which are in turn connected to electric control switches 21. The casing is connected to a ground by a conductor 22 and the switches are connected to a suitable electrical source in which circuit may be located a transformer if necessary. The electric switches 21 and their operating medium form the subject matter of a co-pending application filed June 4, 1934 and Serial No. 729,022.

The electric lamps 16 when employed in lieu of the neon tubes are suitably mounted in the frame and connected in the electric circuit herefore described.

A suitable mirrored reflector 16' is employed in conjunction with the electric lamps 16 for re-

flecting the light rays through the arrows 7 of the casing.

From the foregoing description taken in connection with the accompanying drawing it will be seen that a very simple and practical direction signal has been provided and which may be manufactured and sold at a low cost and one that may be conveniently actuated by the driver of the motor vehicle for the purpose of indicating turns in different directions and eliminating hand signals to indicate such turns.

Having described the invention, I claim:

A direction signal comprising a casing having opposite walls thereof provided with direc-

tion indicating slots, a frame mounted in the casing and including upper and lower and end members and open sides thereon, said open sides being arranged opposite to the slots of said casing, said end members intermediate the ends thereof being offset to provide channeled portions, a partition received by said channeled portions to divide the casing into upper and lower compartments, said end members having the ends thereof offset angularly thereto to provide rests 10 engaging the casing, and illuminating means supported by the frame within the compartments.

JOHN A. SPINA.
